UNITED STATES PATENT OFFICE

PETER SCHLUMBOHM, OF BERLIN, GERMANY

VACUUM COOLER

Application filed October 22, 1928, Serial No. 314,202, and in Germany October 26, 1927.

This invention is directed to an improvement in vacuum coolers whereby the material to be cooled is subjected to a heat exchange with a cooling medium subject to forced evaporation.

Various cooling means for the purpose have been heretofore proposed, such as subjecting the container with the material to be cooled to the action of a refrigerating agent in an encircling vessel, and by a direct evaporation method through the absorption of steam by sulphuric acid. Both of these methods are rather costly in operation, and it is the object of the present invention to produce a system operating on the direct evaporation principle which is both simple of installation and inexpensive to install and maintain.

The invention is illustrated in the accompanying drawings, in which:

20 Figure 1 is a vertical sectional view of the improved refrigerating plant.

Figure 2 is a similar view illustrating the use of a plurality of material containing vessels.

25 The improved refrigerating apparatus includes a container 1. A receptacle 2 for the material to be cooled is of a diameter to fit within and in spaced relation to the wall of the container, the upper end of the receptacle being outwardly flared in semi-circular form to present an edge to bear upon a sealing gasket 3 resting upon the lateral flange at the upper end of the container, so that the receptacle 2 forms in effect a cover for the container. Heat exchange between the cooling medium in the container and the material in the receptacle is increased by ribs 4 radiating from the receptacle.

40 An air inlet pipe 6 leads into the container near its upper end and a diametrically opposite outlet pipe 5 leads to a pump or other suction apparatus. The passage through the pipe 6 is cut off by a control 7 and a manometer 8 is arranged to indicate the control of the incoming air. The pipe 6 may be of the usual double character to provide for cooling the incoming air, if desired.

The material to be cooled is placed in the 50 receptacle 2 and a quantity of water placed

in the container 1 about the receptacle 2. By the passage of air over the cooling agent, the latter is evaporated with the effect of producing heat exchange in the well known manner to cool the contents of the receptacle 2. Incident to the partial vacuum within the container, the receptacle is held under atmospheric pressure to seal the juncture between the cover portion of the receptacle and the container to materially assist in the evaporation of the cooling agent. On the cessation of the air suction, the vacuum is relieved and the receptacle 2 may be simply lifted from the container.

55 In the production of ice cream and the like, a stirrer of any conventional type may be mounted within the receptacle and operated by a turbine wheel 11, with the motive fluid, as water, entering at 13 and exhausting at 14. A heat insulating cover section 15 may be used to overlie the receptacle, the edges of this cover section being down-turned to rest upon the sealing strip 3. A supporting flange connected to the container 1 by an edge clip 12 may be used to support the turbine wheel if the latter is used.

60 In Figure 2, the container 1 is shown as adapted for a plurality of receptacles 2^a and 2^b formed similar to the receptacle 2 in the single form and cooperating with sealing gaskets 3, as in the form shown in Figure 1. In this form, each receptacle 2^a and 2^b is surrounded by a hollow wall container, as 9^a and 9^b, within which and surrounding the receptacle the cooling medium is open to the evaporative influence of the air admitted through the pipe section 6 and withdrawn through the suction pipe 5. Here the hollow wall container acts in a measure as an insulating medium and the use of such eliminates the necessity of an unusually large quantity of cooling medium. To further reduce the quantity of cooling medium, the container in either form may be supplied with masses of material of slight specific heat and suitable shape which will occupy the lower portion of the container, as for example gas rings indicated at 10.

I claim:

1. An evaporator for refrigerating ma-

chines comprising in combination a heat-insulating container for the cooling means open at the top, a packing sheet with openings resting on the rim of said cooling-means container, a metal lid on said cooling-means container also open at the top serving simultaneously as vessel for the reception of the goods to be congealed, said lid dipping into the cooling-means, cooling ribs on the exterior surface of that part of said lid which dips into the cooling means, a pipe conduit merging into the cooling-means container and leading to a pump, a further pipe conduit also merging into the cooling-means container, a manometer in connection with said latter pipe conduit regulating the entrance of air into the cooling-means container, a cock in said latter pipe conduit, a system of double pipes in said latter pipe conduit for the admission of air into the cooling-means container for preliminarily cooling said air, a cover of heat-insulating material over the open upper surface of the lid containing the material to be frozen, whereby the cooling-means container stands under partial vacuum so that the atmospheric outer air presses said lid and cover air-tightly onto the packing sheet.

2. An evaporator for refrigerating machines comprising in combination a heat-insulating container for the cooling-means open at the top, a packing sheet with openings resting on the rim of said cooling-means container, metal lids on said cooling-means container also open at the top serving simultaneously as vessels for the reception of the goods to be congealed, said lids dipping into the cooling-means, cooling ribs on the exterior surface of those parts of said lids which dip into the cooling means, a pipe conduit merging into the cooling-means container and leading to a pump, a further pipe conduit also merging into the cooling-means container, a manometer in connection with said latter pipe-conduit regulating the entrance of air into the cooling-means container for preliminarily cooling said air, covers of heat-insulating material over the open upper surfaces of the lids containing the material to be frozen, whereby the cooling-means container stands under partial vacuum so that the atmospheric outer air presses said lids and covers air-tightly onto the packing sheet.

3. An evaporator for refrigerating machines comprising in combination a heat-insulating container, intermediate vessels in said container for the reception of the cooling-means, the container and the vessels being open at the top, a packing sheet with openings resting on the rim of said container, metal lids on said container also open at the

top serving simultaneously as vessels for the reception of the goods to be congealed, said lids dipping into the cooling means contained in the intermediate vessels, cooling ribs on the exterior surfaces of those parts of said lids which dip into the cooling means, a pipe conduit merging into the evaporator and leading to a pump, a further pipe conduit also merging into the evaporation chamber, a manometer in connection with said latter pipe conduit regulating the entrance of the dlosed air into the evaporation space or container, a cock in said latter pipe conduit, a system of double pipes in said latter pipe conduit for the admission of air into the evaporation space or container for preliminarily cooling said air, covers of heat-insulating material over the open upper surfaces of the lids containing the material to be frozen, whereby the cooling-means containers or intermediate vessels in the evaporator stand under partial vacuum so that the atmospheric outer air presses said lids and covers air-tightly onto the packing sheet.

4. An evaporator for refrigerating machines comprising in combination a heat-insulating container for the cooling means open at the top, a packing sheet with openings resting on the rim of said cooling-means container, a metal lid on said cooling-means container also open at the top serving simultaneously as vessel for the reception of the goods to be congealed, said lid dipping into the cooling-means, cooling ribs on the exterior surface of that part of said lid which dips into the cooling means, a stirrer with in- and outflow of water for the production of ice-cream, means for holding said stirrer on the rim of the cooling-means container, a cover of heat-insulating material over the open upper surface of the lid, an aperture in said cover through which passes the stirrer into the material to be stirred and frozen, a pipe conduit merging into the cooling-means container and leading to a pump, a further pipe conduit also merging into the cooling-means container, a manometer in connection with said latter pipe conduit regulating the entrance of air into the cooling-means container, a cock in said latter pipe conduit, a system of double pipes in said latter pipe conduit for the admission of air into the cooling-means container for preliminarily cooling said air, whereby the cooling-means container stands under partial vacuum so that the atmospheric outer air presses said lid and cover air-tightly onto the packing sheet.

5. An evaporator for refrigerating machines comprising in combination a heat-insulating container for the cooling means open at the top, a packing sheet with opening resting on the rim of said cooling-means container, a metal lid on said cooling-means container also open at the top serving simultaneously as vessel for the reception of the goods

to be congealed, said lid dipping into the cooling-means, cooling ribs on the exterior surface of that part of said lid which dips into the cooling means, masses of slight specific weight and suitable form laid into the cooling means for raising the level of the dosed quantity of cooling-means, a pipe conduit merging into the cooling-means container and leading to a pump, a further pipe conduit also merging 10 into the cooling-means container, a manometer in connection with said latter pipe conduit regulating the entrance of air into the cooling-means container, a cock in said latter pipe conduit, a system of double pipes in 15 said latter pipe conduit for the admission of air into the cooling-means container for preliminarily cooling said air, a cover of heat-insulating material over the open upper surface of the lid containing the material to be frozen, whereby the cooling-means container stands under partial vacuum so that the atmospheric outer air presses said lid and cover air-tightly onto the packing sheet.

20 In testimony whereof I affix my signature.
